J. M. MARTY.

SASH LOCK.

APPLICATION FILED DEC. 15, 1916.

1,250,924.

Patented Dec. 18, 1917.

UNITED STATES PATENT OFFICE.

JOHN M. MARTY, OF CLEVELAND, OHIO.

SASH-LOCK.

1,250,924.

Specification of Letters Patent. Patented Dec. 18, 1917.

Application filed December 15, 1916. Serial No. 137,121.

To all whom it may concern:

Be it known that I, JOHN M. MARTY, a citizen of the United States, residing at Cleveland, in the county of Cuyahoga and 5 State of Ohio, have invented certain new and useful Improvements in Sash-Locks, of which the following is a specification.

My invention relates to improvements in sash locks, and more particularly to that 10 class or type known as "ventilating sash locks," the object being, as the name implies, to enable either one or both sashes to be partly open for ventilation and at the same time locked in such partially opened position 15 against any further movement of the same by any one from the outside.

The primary object of my invention is to provide a generally improved lock of this 20 class which will be exceedingly simple in construction, cheap of manufacture, and efficient in use.

A further object is the provision of a lock 25 which may be used interchangeably on the inner side of the upper cross rail of either the upper or the lower sash, the only change necessary in adapting the same to the upper or the lower sash being in the mounting of the same and providing the lock with a different form of hand actuating lever in accordance with the change in position or 30 location of the lock.

A still further object of the invention is the provision of an improved lock of this 35 class which will not only positively lock the upper and lower sashes in their respective adjusted position but will also positively lock each sash independently of the other.

A still further object is the provision of 40 an improved lock of this class which cannot be tampered or interfered with by any one from the outside when the sash is in a partially open or ventilating position.

With above mentioned and other ends in view, my invention consists in the novel construction, arrangement, and combination of 45 parts, hereinafter described, illustrated in one of its embodiments in the accompanying drawings, and particularly pointed out in the appended claims.

Referring to the drawings, forming a part 50 of this specification, Figure 1, is a side elevation of the improved ventilating sash lock as applied to the upper cross rail of an up- per window sash.

Fig. 2, a front view of the same.

Fig. 3, a side elevation of the same as applied to the upper cross rail of the lower sash.

Fig. 4, a front view of the same.

Fig. 5, a view of the underside of the at- 60 taching lock casing or housing, detached.

Fig. 6, a central longitudinal sectional view of the same, illustrating the internal operating mechanism, more in detail.

Fig. 7, a rear view of the lock casing or 65 housing.

Fig. 8, a perspective view of one of the lever actuated crank arms within the casing for actuating the sash locking plunger mem- 70 bers or rods.

Fig. 9, a side elevation of the main actuating or sash releasing hand lever, detached.

Similar numerals of reference designate like parts throughout all the figures of the drawings. 75

The improved sash lock comprises an at- taching casing or housing 1, adapted to be attached to the upper central portion of the upper cross rail 2, of the window sash. The lock casing or housing 1, is adapted to be at- 80 tached to the cross rail 2, of the sash by means of screws 2^a, and the casing or housing 1, is provided at its ends with plunger guide or bearing openings 1^a.

The window frame engaging plunger 85 members or rods 3, are slidably mounted in the plunger guide members 1^a, and extend outwardly from the sash casing 1, and through the guide members, said plunger members 3, being preferably supported at 90 their outer ends in plunger guide members 4, said guide members 4, in the present instance, being in the form of brackets secured to the cross rail 2, of the sash by means of screws 4^a.

As a means of positively locking the sash in adjusted positions and independently of each other, the inner or adjacent sides of the window frame are provided with the rack members 5, provided with a series of suit- 100 ably spaced plunger receiving openings 5^a. As a means of positively holding or pressing the plunger members 3, in their projected or locked positions, the inner ends of the plunger members 3, are spaced from each other within the casing 1, and a compression spring 6, is mounted on and interposed be- 105 tween the inner ends, and as a means of providing a suitable bearing for the ends of the spring 6, and the actuating mechanism 110

hereinafter described, said inner or spaced ends of the plungers or rods 3, are preferably provided with cross pins 7.

As a means of simultaneously actuating or 5 retracting the plunger members 3, against the resistance of the spring 6, and thereby withdrawing the same from locking engagement with the rack 5, crank arms 8, are transversely pivoted in the casing 1, through 10 the medium of cross bearing screws 8^a, said arms or members extending toward each other at the top and having their lower arms or member 8^b, loosely connected to the inner ends of the plunger members 3, said 15 arms being preferably bifurcated as at 8^c, and straddling the inner ends of the plunger members as shown most clearly in Figs. 5, and 8, of the drawings. The bifurcated arms or members 8^b, are adapted to bear against 20 the cross pins 7, only when manually operated for retracting the plungers 3, against the resistance of the spring 6, by the mechanism hereinafter described, and the loose connection permits the plungers to be moved 25 inwardly against said spring independently of each other and of said crank arms and their actuating mechanism.

As a means of conveniently assembling the parts and simultaneously actuating the 30 crank arms 8, as well as adapting the improved lock to upper and lower sashes as shown in Figs. 1, and 3, of the drawings, an interchangeable hand actuating lever 9, of a form adapted to the particular sash is re- 35 movably mounted in transverse openings 1^b, of the lock casing or housing 1.

As a convenient means of readily assembling the parts as well as operatively connecting the lever 9, to the crank arms 8, 40 whereby the latter will be simultaneously actuated to correspondingly actuate the plungers 3, the hand lever 9, is provided with oppositely disposed or laterally extending 45 projections 9^b, said projections in the present instance, being formed by means of a cross pin or bar passing through the intermediate portions of the lever 9, directly between the crank arms 8, and beneath the horizontally extending portions thereof, so 50 that when the hand lever 9, is moved outwardly and upwardly away from the sash rail 2, the engagement of the projections 9^b, with the arms 8, of the crank arm will operate the latter in an obvious manner.

As a means of preventing the unauthorized operation of the hand lever 9, used on the upper cross rail 2, of the lower sash, by any one from without and while the lower sash is partially elevated for ventilation (as 60 by reaching in under the lower sash and upwardly with the hand or by the use of a stick or other implement) the lower depending portion of the hand lever, 9, is preferably provided with a guard plate 9^c, it being obvious that such guard plate 9^c, will

prevent the operation of the lever 9, from below in the manner stated and at the same time will permit of the operation of the handle lever 9, by someone from within.

As a means of adapting the improved lock 70 for use on the upper sash, the improved lock casing or housing 1, together with the plungers 3, and guide members 4, are mounted on the inner face side of the upper cross rail 2, of the upper sash, and the handle 75 5 or lever 9, for use in such connection is extended as at 9^d, to extend down and swing with a pendulum like motion in front of the inner side of the upper sash as suggested in Fig. 1, of the drawings, so that when the 80 handle 9^d, is swung inwardly or away from the sash to the requisite distance the plungers 3, will be withdrawn or retracted from engagement with the plates or racks 5.

It will thus be seen that the only change 85 necessary in adapting the improved lock for use on the upper sash instead of the lower sash is simply a change in the manner of mounting or attachment and the substitution of a pendulum like lever for the form 90 of lever shown in Figs. 3, and 4, of the drawings.

From the foregoing description, taken in connection with the accompanying drawings, the operation and advantages of my 95 invention will be readily understood.

Having thus described one of the embodiments of my invention, what I claim and desire to secure by Letters Patent, is,—

1. A sash lock, comprising an attaching 100 casing, spaced longitudinal plunger bars therein extending from opposite ends thereof, a compression spring in said casing between said spaced plungers and normally projecting the latter, crank arms extending 105 toward each other and pivoted transversely in said casing and having bifurcated depending portions loosely connected to and adapted to draw said plungers toward each other against said spring and to permit the 110 latter to project said plungers independently of each other, and an actuating lever transversely pivoted in and depending in front of said casing and provided with oppositely 115 disposed arms engaging beneath and operating said crank arms to retract said plunger members when said actuating lever is elevated.

2. A sash lock, comprising a casing provided with oppositely disposed guide ends, 120 window frame engaging plunger members mounted in said guide ends and spaced apart in said casing, cross pins in the spaced ends of said plunger members, a compression spring interposed between said cross pins in the spaced ends of said plunger members, crank arms pivoted in said casing above and loosely connected to said cross pins of said plunger members, and having 125 their upper arms extending toward each 130

other, said loose connection permitting said plungers to ride and be moved inwardly independently of each other and of said crank arms, and an operating lever transversely 5 pivoted in said casing above said spring and provided with oppositely disposed projections engaging with said inwardly extending arms and adapted to move said plunger members and cross pins toward each other 10 against the resistance of said spring when said lever is moved to operate said crank arms.

3. A sash lock, comprising a sash-rail attaching casing provided with plunger guides, window frame engaging plunger members mounted in said guides and spaced apart in said casing, plunger guide brackets carrying the outer ends of said plunger members, a compression spring interposed 15 between the spaced ends of said plunger members, crank arms loosely connected to said plunger members opposite the ends of said spring and having their upper arms extending toward each other, and an operating 20 lever in said casing between said crank arms and provided with lateral projections extending within the planes of and engaging beneath said inwardly extending upper arms and adapted to retract said plunger members 25 against the resistance of said spring only when said lever is moved in the one direction to operate said crank arms and to permit the independent movement of the latter.

35 4. A sash lock, comprising a casing, window frame engaging plunger members mounted therein and spaced from each other, a compression spring interposed between the spaced ends of said plunger members, cross pins in said spaced ends of said plunger members and abutting against the ends of said spring, crank arms transversely 40 pivoted in said casing and provided with depending bifurcated arms straddling said spaced ends of said plunger members and

abutting against said cross pins, whereby the latter and said plunger may be moved inwardly independently of each other and of said crank arms, said crank arms having inwardly extending horizontally disposed 50 arms above said spring, and an operating hand lever pivoted in said casing and provided with oppositely disposed projections engaging said horizontally disposed arms when moved in the one direction only and 55 adapted to operate said crank arms and retract said plunger members against said spring.

5. A sash lock, comprising a casing, window frame engaging plunger members 60 mounted therein and spaced from each other, a spring interposed between the spaced ends of said plunger members, attaching guide members for the outer ends of said plunger members, cross pins in said 65 spaced ends of said plunger members and abutting against the ends of said spring, crank arms transversely pivoted in said casing and provided with depending bifurcated arms loosely straddling said spaced 70 ends of said plunger members and abutting against said cross pins to permit of the independent riding movement of said plunger members independently of said crank arms, said crank arms having inwardly extending 75 horizontally disposed arms above and movable vertically in the plane of said plunger members, and an operating hand lever in said casing and provided with oppositely disposed projections loosely engaging underneath said horizontally disposed arms and adapted to operate said crank arms and retract said plunger members against the resistance of said spring.

In testimony whereof I have affixed my 85 signature in the presence of two witnesses.

JOHN M. MARTY.
